United States Patent Office

Des. 215,472
Patented Sept. 30, 1969

215,472

FOOD SPREADER

Charles R. Potts, Royal Oak, Mich.
(20214 E. 15 Mile, Mount Clemens, Mich. 48043)

Filed Jan. 31, 1969, Ser. No. 15,585

Term of patent 3½ years

Int. Cl. D7—99

U.S. Cl. D44—29

FIG. 1

FIG. 2

FIG. 3

FIG. 4

FIG. 5

FIGURE 1 is a perspective view of a food spreader embodying my new design;

FIGURE 2 is a side elevational view;

FIGURE 3 is an elevational view from the opposite side;

FIGURE 4 is a top plan view; and

FIGURE 5 is an end elevational view.

I claim:

The ornamental design for a food spreader, as shown.
